UNITED STATES PATENT OFFICE.

ERNST F. KLEMME, OF MILWAUKEE, WISCONSIN.

VENTILATOR.

1,236,184.

Specification of Letters Patent. Patented Aug. 7, 1917.

Application filed May 28, 1915. Serial No. 30,888.

To all whom it may concern:

Be it known that I, ERNST F. KLEMME, a citizen of the United States, and resident of Milwaukee, in the county of Milwaukee and State of Wisconsin, have invented new and useful Improvements in Ventilators, of which the following is a description, reference being had to the accompanying drawings, which are a part of this specification.

10 This invention relates to ventilators for water closets, and has for its object to provide means for automatically opening up a ventilating connection between the closet bowl and the vent pipe when the closet seat 15 is raised, and closing said connection at other times.

Referring to the accompanying drawings, in which like characters of reference indicate the same parts in the different views,

20 Figure 1 is a side view of a water closet provided with a ventilator constructed in accordance with this invention;

Fig. 2 is an enlarged view of the ventilator connection;

25 Fig. 3 is a longitudinal sectional view thereof; and,

Fig. 4 is a transverse sectional view thereof.

In these drawings 10 indicates a water 30 closet bowl having a hinged cover 11, as usual, and 12 is the flushing tank connected with the bowl by a water pipe 13. A T 14 is fitted in the water pipe and threaded therein is the reduced neck portion of a horizontal cylindrical casing 15. A tubular connection 16 is threaded in the rear end of the casing and the opening in its end is adapted to be closed by a valve member 17 hinged within the casing by being fixed on the 35 square central portion of a shaft 18 which is journaled across the casing. A lever 19 is fixed on one end of shaft 18 and its upper end is connected to a spring 20 which is attached to the casing and tends to keep the 40 valve closed. The lower end of lever 19 is connected by a link 21 to the lower end of a vertical lever 22 which is fulcrumed in a bracket 23 on the flushing tank 12, and the upper end of said lever is bent forwardly 45 to be engaged by the closet seat cover when the latter is in its open position. The weight 50 of the closet seat cover bearing against the

end of lever 22 is sufficient to swing the valve 17 to its open position against the action of spring 20 so that as long as the 55 cover is open the valve is open, but when the cover is closed the spring holds the valve closed.

The end of the tubular connection 16 is suitably connected with the plumbing vent 60 pipe 24 as by threading it through an opening therein so that when the valve is open there is a direct ventilating connection from the closet bowl to the vent pipe, but as this connection is automatically closed again as 65 soon as the closet seat cover is closed there is no danger of the vent pipe being in communication with the interior of the room.

The advantages of the invention are obvious, as a complete ventilation of the closet 70 bowl will be automatically effected whenever the closet seat cover is opened and the ventilating connection is closed when the cover is closed.

Should water collect in the casing it may 75 be drained therefrom by removing a drain plug 25 which is threaded in the bottom thereof.

What I claim as new and desire to secure by Letters Patent is:

80

1. A water closet ventilator, comprising a casing connected with the closet bowl water supply pipe, a shaft journaled across the casing, a valve thereon for closing the opening through the casing, and a lever on the 85 shaft outside of the casing by which the valve may be opened and closed.

2. A water closet ventilator, comprising a cylindrical casing connected with the closet bowl water supply pipe, a tubular connection fitting therein and connected with the vent pipe, a shaft journaled across the casing, a valve thereon for closing the opening through the tubular connection, a lever on the shaft, a spring engaging the lever for 95 closing the valve, a lever positioned to be engaged by the closet seat cover, and a link connecting the two levers.

In testimony whereof, I affix my signature, in presence of two witnesses.

ERNST F. KLEMME.
